C. W. WYMAN

FUSE

Filed May 16, 1919

UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

FUSE.

Application filed May 16, 1919. Serial No. 297,531.

To all whom it may concern:

Be it known that I, CHARLES W. WYMAN, a citizen of the United States, residing at Claremont, in the county of Sullivan and State of New Hampshire, have invented certain new and useful Improvements in Fuses, of which the following is a full, clear, and exact specification.

This invention relates to fuses and more especially to a fuse and fuse container for use with heavy currents and on machines liable to receive rough usage.

One object of the present invention is to provide an improved fuse container. Another object of the present invention is to provide an improved construction whereby the contacts in a fuse box cannot accidentally be closed. Still another object of the present invention is to provide an improved construction whereby any wear between the contacts is automatically adjusted and whereby the contact within the fuse box is automatically made upon closure of the fuse box. These and other objects and advantages of the present invention will, however, hereinafter more fully appear.

In the accompanying drawings, I have shown for purposes of illustration one embodiment which my invention may assume in practice.

In these drawings,

Fig. 1 is a plan view of my improved construction, parts thereof being broken away to facilitate illustration.

Fig. 2 is a side elevation thereof, a part being shown in section on the line indicated by 2-2 Fig. 1.

Fig. 3 is a transverse sectional view substantially on the line 3-3 Fig. 1, the open position of the cover being indicated in dotted lines.

In this illustrative construction, I have shown a fuse box of which the lower and larger part 1 serves as a container for a fuse when the box is closed, the box being adapted to be attached to a support by forwardly projecting arms 2 which carry the fuse box in spaced relation to the support. When in use, the container 1 is preferably closed by a cover 3 herein shown as hingedly connected to the lower part of the box as by bolts 4 passing through lugs 5 and 6 on the cover and box respectively. When the cover is in closed position on the box, an overhang-

ing flange 7 on the cover prevents water or dirt from working into the box through the joint between the latter and the cover. While any form of latch may be used for retaining the cover in closed position, I preferably use for this purpose a longitudinally movable locking bolt 8 carried by one of the lugs 2 and a separate lug 9 mounted on the lower part of the box, the bolt being pressed into locking position by a spring 10 which abuts against one end of the bolthead and one side of the lug 2 and preferably surrounds a controlling pin 11 having its outer end 11' bent upwardly to facilitate the operation of the controlling rod to retract the bolt from an apertured lug 12 formed on the cover and permitting the cover to be opened. However, when the cover is moved toward closing position, the bolthead 8 will prevent the closure of the box until the bolt is retracted by manipulation of the latch or handle 11'. As shown, this locking mechanism is preferably placed adjacent the support to which the fuse box is attached in order that the latch may not accidentally be caught by a passing object in such a manner as to loosen the cover and thereby permit an accidental opening thereof.

Carried within the fuse box and preferably in spaced relation to the walls thereof are a series of insulating plates 13 and 14, 85 preferably mounted on lugs 15 herein shown as formed integral with the box itself. A relatively heavy insulating block 16 is also preferably carried within the container and preferably on the insulating plate 14 to support a plurality of fixed contacts 17 herein shown as rigidly connected to the insulating block 16 as by means of bolts or screws 18. The unit comprising the block 16 and the contacts carried thereby as well as the thinner insulating block 14 are preferably detachably secured to the lower part of the box as by means of screws 19, the latter being protected from injury when the box is set down upon a part of a machine, 100 by a lug 20 carried on the bottom of the container 1. Electrical contact is preferably made with the contacts 17 by means of cables 21 which pass through insulating rings 22 preferably carried by the box, and connect with upstanding arms 23 herein shown as formed integral with the contacts 17, the ends of the cables being detachably secured

to these arms as by plates 24 and bolts 25. By this improved construction, the base of the fuse box may be rigidly secured to a machine such as a mining machine, the cover 5 may be placed in closing position and held in that position by a locking means which will not accidentally be unlocked, and the electrical cables are attached to a fixed part of the fuse box, thereby preventing the wearing of the cables as is the case when the cables are moved with a movable part of a fuse box during the changing of a fuse.

The cover 3 is also insulated by a plurality of insulating blocks 26 and 27, the 15 first of which is attached to the cover in spaced relation thereto against suitable lugs 28 by screws 29. This insulating block 26 is preferably grooved longitudinally as shown at 30 to receive a spring 31 which is detachably secured to this insulating block as by a screw 32 which also holds the insulating block 27 to the block 26. The flexible ends of the springs 31 normally act against insulating blocks 33 disposed preferably at 20 opposite ends of the fuse box and preferably carried by movable contacts 34 which are adapted to make contact with the fixed contacts 17 when the box is closed. These movable contacts 34 are preferably carried 25 on a cylindrical insulating tube 35 which may be passed through the contacts and through an aperture 36 formed in the insulating block 27, the contacts 34 being held in their proper position on the tube 35 by 30 the fusible element 37 which passes longitudinally through the tube 35 and is detachably secured to the movable contacts as by screws 38. As is clearly shown in Fig. 2, the aperture 36 in the insulating member 27 is 35 relatively large, permitting a transverse movement of the insulating tube 35 and the parts carried thereby relative to the cover under the influence of the spring 31 during the opening and closing of the cover.

40 By this improved construction it will be noted that a lost motion connection is provided between the fuse carrying member 35 and the cover, and that a resilient means is also provided for normally pressing the movable and fixed contacts together when the box is closed and thereby automatically compensating for any wear on the contacts. By comparing Figs. 2 and 3, it will be noted that when the cover is moved toward closing 45 position and the lug 12 strikes the bolthead 8, the movable contacts do not touch the fixed contacts, but when the latch is retracted to permit a complete closing of the box, the contact is made within the box before the 50 cover is completely closed. By the improved construction used, it will also be noted that the fuse element 37 holds the fuse retainer 35 in a fixed relation to the movable contacts 34 and that other means are not necessary 55 for holding the element 35 in its proper re-

lation to the cooperating parts, this tube 35, when the cover is closed, being automatically aligned with a blow hole 39 formed preferably in one end of the container through which all fused parts of the fusible member 37 will be blown when the fuse gives way under a high current, thereby preventing arcing by the passage of a current from one contact to another through small globules of fuse material which would otherwise gather 75 in the bottom of the fuse carrying tube 35.

It is thus seen that I have provided a strong, ruggedly constructed fuse box which may be bolted to the side of a machine such as a mining machine which receives very 80 rough treatment while in use. It will further be seen that I have provided a fuse box in which the fusible element may be easily renewed and in which the parts may be readily assembled in their correct position by 85 an unskilled operator. It should also be noted that another feature of the present invention is the provision of a means for normally preventing closure of the contacts when the cover is swung toward closing position, thereby making the device fool-proof. 90 In the event that the current were not turned off from the motor during the replacement of a fuse and a short circuit existed, it will be obvious that were the box to be arranged 95 so as to close automatically and without check upon movement toward closing position, that, by reason of the fact that the circuit would close before the box was completely closed, the sudden expansion of the 100 air within the box, due to blowing of the new fuse, would cause the box to blow directly open again, possibly injuring the operator. If, however, as in the present case, the operator naturally places his left hand 105 upon the box while drawing out the latch with his right hand, there will obviously be sufficient pressure normally on the top of the box to prevent its blowing open even though the fuse may be blown instantly 110 upon the box reaching closed position.

While I have in this application specifically described one embodiment which my invention may assume in practice, it is to be understood that this form is used for illustrative purposes only and that the invention 115 may be modified and embodied in various other forms without departing from its spirit or the scope of the appended claims.

What I claim as new and desire to secure 120 by Letters Patent is:

1. In a fuse box, a fuse and container therefor, a cover therefor, and common means automatically operative in all positions of the box to prevent closure of the 125 container by the cover when the latter is moved toward closed position and to prevent said fuse from being operative until said container is substantially closed.

2. In a fuse box, a fuse container, a cover, 130

therefor, and means including a member operative when the cover is in full closed position to maintain the box closed automatically operative in all positions of the box to interrupt closing movement of the cover when the latter is moved towards closed position.

3. In a fuse box, a fuse container, a cover therefor, and means including a member operative when the cover is in full closed position to interlock with the latter to maintain said cover closed, automatically maintained in all positions of the box in a position to interrupt closing movement of said cover until deliberately moved to an inoperative position.

4. In a fuse box, a fuse container, a cover therefor, and means including a member operative when the cover is in full closed position to interlock with the latter to maintain said cover closed, automatically maintained in all positions of the box in a position to interrupt closing movement of said cover until deliberately moved to an inoperative position and automatically moving, on cessation of the force employed to move the same to inoperative position, to a position to lock said cover.

5. In a fuse box, a fuse container, a cover therefor, and means operative in any position of the fuse box for normally preventing closure of said container by said cover when said cover is moved toward closing position, said means also preventing opening thereof when closed.

6. In a fuse box, a fuse enclosing insulating member, supporting means therefor, and a fusible member extending through said member and holding the same in position in said supporting means.

7. In a fuse box, a fuse enclosing member, a support therefor movable relatively thereto, a portion of said member being surrounded by said support, and a lost motion connection between said enclosing member and said support operative upon movement of said support.

8. In a fuse box, a fuse enclosing member, a movable support therefor adapted to be substantially adjacent said member, and a lost motion connection between said member and said support, said connection being adapted to allow said member to be guided into operative position upon movement of said support.

9. In a fuse box, a fuse enclosing member movable in a plurality of directions, a support movable relative to said member, a lost motion connection between said member and

10. said support including means adapted to limit the amount of movement of said enclosing member by controlling the lost motion connection, said lost motion connection being operable upon movement of said sup-

port, and means for holding said fuse holder 65 in a predetermined position relative to said support.

10. In a fuse box, a fuse enclosing member movable in a plurality of directions, a movable support therefor, a lost motion connection between said member and said support including means adapted to limit the amount of movement of said enclosing member by controlling the lost motion connection, said lost member connection being operable upon 70 movement of said support and resilient means for holding said fuse holder in a predetermined position relative to said support.

11. A fuse box, comprising a plurality of relatively movable members, a contact carried by one of said members, a cooperating contact carried by another of said members, an insulating member enclosing a fuse movable with one of said contacts, said contacts being detachably connected to said insulating member, and a lost motion connection between one of said contacts and its supporting member.

12. A fuse box comprising a plurality of relatively movable members, a contact carried by one of said members, a cooperating contact carried by another of said members, an insulating member enclosing a fuse movable with and carried by one of said members, one of said contacts being movable with 95 and relatively to said insulating member, a lost motion connection between said last named contact and movable member, and means for holding said last named elements 100 in predetermined relative positions.

13. In a fuse box, a supporting means, an insulating member carried thereby, a member movable relatively thereto and operatively connected thereto by a lost motion connection, and a replaceable fusible member carried in said last named member.

14. In a fuse box, a supporting means, an insulating member carried thereby, a member movable relatively thereto and operatively connected thereto by a lost motion connection, a replaceable fusible member carried in said last named member, and means for retaining said movable member on said supporting means.

15. In a fuse box, a movable supporting means, a member substantially rigidly carried thereby, a member movable in a plurality of directions relatively thereto and carried thereby, a fusible member carried in said last named member, and means for retaining said movable member in a predetermined position relative to said supporting means upon movement of the same.

16. In a fuse box, a supporting means, a member carried thereby, an open end member movable relatively thereto and carried thereby, a fusible member carried in said last named member, and means for retaining

- said movable member in a predetermined position relative to said supporting means.
17. In a fuse box, a supporting means, a member carried thereby, a member movable relatively thereto and carried thereby, a fusible member carried in said last named member, and a contact detachably carried by said movable member.
18. In a fuse box, an insulating member, a plurality of contacts through which said insulating member extends, and a fuse element adapted to hold said contacts on said member.
19. In a fuse box, an insulating member, a plurality of contacts through which said insulating member extends, and a fuse element passing through said member and attached to said contacts and adapted to hold said contacts on said member.
20. In a fuse box, an insulating member, a plurality of contacts through which said insulating member extends, a fuse element passing through said member and attached to said contacts and adapted to hold said contacts on said member, and a member adapted to hold said insulating member and having provision for permitting a relative movement of said members.
21. In a fuse box, an insulating member, a plurality of contacts thereon, a fuse element passing through said member and attached to said contacts and adapted to hold said contacts on said member, a member adapted to hold said insulating member and having provision for permitting a relative movement of said members, and means for holding said members in predetermined relative positions.
22. In a fuse box, an insulating member, a plurality of contacts thereon, a fuse element passing through said member and attached to said contacts and adapted to hold said contacts on said member, a member adapted to hold said insulating member and having provision for permitting a relative movement of said members, and means comprising a spring and cooperating insulating members carried by said contacts for holding said members in predetermined relative positions.
23. In a fuse box, a container, a member movable relatively thereto, fixed contacts carried by one of said elements, a movable contact carried by the other of said members, and means automatically operative irrespective of the position of the box for preventing movement of said member to final position to permit closing of the circuit through the fuse box.
24. In a fuse box, a container, a member movable relatively thereto, fixed contacts carried by one of said elements, movable contacts carried by the other of said elements, and means comprising a latch automatically operative irrespective of the position of the box for preventing movement of said member to final position to permit closing of the circuit through the fuse box.
25. In a fuse box, a container, a member movable relatively thereto, fixed contacts carried by one of said elements, movable contacts carried by the other of said elements, and means comprising a latch automatically operative irrespective of the position of the box for preventing movement of said member to final position to permit closing of the circuit through the fuse box, said latch being movable to permit closure of said container.
26. In a fuse box, a container, a cover movable relatively thereto, fixed contacts carried by one of said elements, movable contacts carried by the other of said elements, and means comprising a latch automatically operative irrespective of the position of the box for preventing movement of said member to final position to permit closing of the circuit through the fuse box, said latch being movable to permit closure of said container and to retain said cover in closing position.
27. In a fuse box, a fixed container, a hinged cover movable relatively thereto, a set of fixed contacts carried by said container, a set of movable contacts carried by said cover, a fuse element between one set of contacts, means for guiding said movable contacts and for forcing said contacts away from the cover when the latter is in open position, and means for preventing closure of said container by said cover and for holding the contacts separated, said means being adjustable to permit said cover to close the container, the sets of contacts being brought together previous to the closure of the container.
28. In a fuse box, a container, a cover therefor, a blow hole in said container, and a fuse carrying member carried by said cover and adapted to align with said blow hole when the container is closed by said cover.
29. In a fuse box, a container adapted to be attached to a support, a cover for said container, and means disposed for operation only on the side thereof to be fastened to the support for holding said cover in closed position on said container.
30. In a fuse box, a container adapted to be attached to a support, a cover for said container, and means carried by the fuse box and disposed for operation on the side thereof to be fastened to the support for holding said cover in closed position on said container.
31. In a fuse box, a container adapted to be attached to a support in spaced relation thereto, a cover for said container, and means carried by the fuse box and disposed for operation on the side thereof to be

fastened to the support for holding said cover in closed position on said container.

32. In a fuse box, a container, a cover movable relatively thereto, a fusible element carried by one of said first named elements, a blow hole carried by the other of said elements, and means whereby said fusible element is aligned with said blow hole when the cover is in closed position.

33. In a fuse box, a container, a cover movable relatively thereto, a fuse carrying member having a hole therein, a blow hole in one of said first named elements, and means whereby said hole in the member is aligned with the blow hole when the cover is in closed position.

34. In a fuse box comprising a main receptacle and a cover, a hinged connection between said cover and main receptacle, contacts connected with the line and arranged in said main receptacle, contacts having a lost motion connection with the cover, insulating means between the contacts and the cover, a single spring cooperating with both contacts to provide them with a resilient mounting, and a fuse extending between said contacts.

35. A fuse box comprising a main receptacle, a hinged connection between the cover and main receptacle, contacts connected to the line and carried in the main receptacle, contacts flexibly mounted on but insulated from the cover, an insulating fuse holder extending between said contacts, and a fuse in said holder operative to maintain said holder in fixed relation to said contacts.

36. In a fuse box, a fuse container, a cover therefor, contacts carried by said container, contacts carried by said cover, one of said sets of contacts being yieldingly mounted on its supporting member and adapted to move relatively thereto when engaged by the other set of contacts during closing movement of the cover, means for limiting the movement of said yieldingly mounted set of contacts away from its supporting member, and means automatically operative to interrupt closing movement of said cover before said sets of contacts engage.

37. In a fuse box, a fuse container, a cover therefor, contacts carried by said container, contacts carried by said cover, a fuse connecting certain of said contacts, one of said sets of contacts being yieldingly mounted on its supporting members and adapted to move relatively thereto on engagement with the other set of contacts during closing movement of the cover, means for limiting the movement of said yieldingly mounted set of contacts away from its supporting member, and means automatically operative to interrupt closing movement of said cover before said sets of contacts engage.

38. In a fuse box, a fuse container, a cover therefor, contacts carried by said container, contacts carried by said cover, one of said sets of contacts being yieldingly mounted on its supporting member and adapted to move relatively thereto on engagement with the other set of contacts during closing movement of the cover, means for limiting the movement of said yieldingly mounted set of contacts away from its supporting member, and means automatically operative to interrupt closing movement of said cover before said sets of contacts engage, said last mentioned means being movable to permit completion of closing movement of said cover and when the latter is in closed position cooperating therewith to lock the same closed.

39. In a fuse box, a fuse container, a cover therefor, contacts carried by said container, contacts carried by said cover, a fuse connecting certain of said contacts, one of said sets of contacts being yieldingly mounted on its supporting member and adapted to move relatively thereto when engaged with the other set of contacts during closing movement of the cover, means for limiting the movement of said yieldingly mounted set of contacts away from its supporting member, and means automatically operative to interrupt closing movement of said cover before said sets of contacts engage, said last mentioned means being movable to permit completion of closing movement of said cover and when the latter is in closed position cooperating therewith to lock the same closed.

40. In a fuse box, a fuse container, a cover therefor, contacts carried by said container, contacts carried by said cover, a fuse connecting certain of said contacts, one of said sets of contacts being yieldingly mounted on its supporting member and adapted to move relatively thereto on engagement with the other set of contacts during closing movement of the cover, means for limiting the movement of said yieldingly mounted set of contacts away from its supporting member whereby said sets of contacts engage at about the instant when the side of the cover most remote from the container comes into the same plane as the edge of the container, and means automatically operative to interrupt closing movement of said cover before said sets of contacts engage, said last mentioned means being movable to permit completion of closing movement of said cover and when the latter is in closed position cooperating therewith to lock the same closed.

41. In combination, a container, a cover therefor, contact means carried by said container, contact means carried by said cover, one of said means being yieldingly mounted on its supporting member and adapted to

move relatively thereto when engaged by the other means during closing movement of the cover, means for limiting the movement of said yieldingly mounted contact means away from its supporting member, and means always automatically operative to interrupt closing movement of said cover before said means engage each other.

42. In combination, a container, a cover therefor, contact means carried by said container, contact means carried by said cover, one of said means being yieldingly mounted on its supporting member and adapted to move relatively thereto on engagement with the other of said means during closing movement of the cover, means for limiting the movement of said yieldingly mounted contact means away from its supporting member, and means always automatically operative to interrupt closing movement of said cover before said contact means engage each other, said last mentioned means being movable to permit completion of closing movement of said cover and when the latter is in closed position cooperating therewith to lock the same closed.

43. Fuse supporting means comprising a holder, contacts associated therewith, a fuse enclosing member having fusible material therein, said contacts and member being adapted to be relatively movable, and means whereby said holder maintains said contacts in their associated position.

44. Fuse supporting means comprising a holder, contacts movable relatively thereto, a fuse enclosing member adapted to be movable relative to said contacts and having

fusible material therein, and means whereby said holder is adapted to limit the movement of said contacts.

45. Fuse supporting means comprising a holder, contacts associated therewith, a fuse enclosing member having fusible material therein, said contacts and holder being adapted to be relatively movable, and means whereby said holder is adapted to control said relative movement of said contacts.

46. Fuse supporting means comprising a support, a plurality of contacts associated therewith, a fuse enclosing member having fusible material therein, said contacts being adapted to be relatively movable, and means whereby said member is adapted to cause substantially uniform operation of said contacts.

47. In combination, a support having a longitudinal recess and a leaf spring disposed therein, and a fuse member associated with said support and having means associated therewith extending into said recess to engage said spring.

48. In combination, a support having a recess and yieldable means disposed therein, a portion projecting therefrom having a longitudinal recess, and a fuse member adapted to extend through said latter recess and having a contact disposed on the ends thereof provided with means extending into said first mentioned recess to engage said yieldable means to operatively control said fuse member.

In testimony whereof I affix my signature.

CHARLES W. WYMAN.
